 1949, Serial No. 111,448

20 Claims. (Cl. 123—103)

1

This invention relates to the control of supercharged internal combustion engines for use in airplanes. In the copending application of John Dolza et al., Serial No. 449,918, filed July 6, 1942, and now abandoned, there is disclosed an engine controller having a main control lever operated by the pilot's throttle lever in the cockpit of the plane. By moving the lever, the throttle is partly opened and there is effected a selection of the engine intake pressure to be maintained by the controller. As the altitude increases, a hydraulic servo-motor operates automatically to increase the throttle opening so that the selected pressure will be maintained until critical altitude for the selected pressure is reached, the throttle then being wide open. The main control lever operates the propeller pitch control lever so that the governed speed of the engine is coordinated with the pressure selection thereby controlling the power output of the engine.

The mechanical operation of the propeller pitch control lever by the main control lever of the controller presents difficulties in certain installations, particularly where there is a substantial distance between the propeller governor and the engine near which the controller is located. In such installations, the transmission of mechanical motion between the control lever and the propeller governor adjusting lever is a serious problem. Therefore, it is an object of the present invention to provide for the movement of the governor adjusting lever by an electric servo-motor which can be located near the governor if desired and which is under the control of the main control lever of the throttle controller.

The operation of the throttle by the controller of the Dolza et al. application depends upon the maintenance of a supply of oil under pressure and in preventing the oil from becoming too cold and viscous. Since the installation and maintenance of electric circuit is much simpler and less expensive than in the case of hydraulic pipe lines, it is an object to provide for the automatic actuation of the throttle valve by an electric servo-motor.

Further objects and advantages of the present invention will be apparent from the following description, reference being had to the accompanying drawings wherein a preferred embodiment of the present invention is clearly shown.

In the drawings:

The figure is a diagram of an embodiment of 55 the present invention.

2

In the figure, an engine 20 drives a propeller 21 having variable pitch blades adjusted by a governor 22 controlled by a lever 23. Engine 20 drives a shaft 24 operating a supercharger 25 having an outlet 26 controlled by a throttle valve 27 and leading to a carburetor 28 connected by manifold 29 with the engine intake ports. The throttle 27 is adjusted by a controller 30 having an aneroid bellows 31 and a bellows 32 connected by pipe 33 with intake manifold 29 of the engine 20. A bar 34 connects the free ends of the bellows 31 and 32 and carries a pivot 35 for a lever 36 providing a plate 37 insulatingly supporting segments 38 and 39 spaced by a gap 40. A spring 41 urges lever 36 against a datum or pressure selecting cam 42 connected with a shaft 43 operated by a main control lever 44. The construction of the bellows is disclosed in detail in the copending application of John Dolza et al., Serial No. 449,918, filed July 6, 1942. The bellows contain springs of such calibration that the relation of movement of pivot 35 to changes in pressure in bellows 32 is substantially a linear relation.

25 Main control lever 44 is manually operated by the pilot's throttle lever located in the cockpit of the airplane. The setting of lever 44 determines the position of the datum cam 42 and the manual setting of the throttle valve 27. As lever 44 is moved clockwise as indicated by arrow 44a, valve 27 is moved clockwise by virtue of a lever 45 connected with shaft 43, and by link 46 with a lever 47 connected with a shaft 48, gear train 49 and 50 connecting shafts 48 and 51 and gear train 52 and 53 connecting shafts 51 and 54, the latter being connected with valve 27. An automatic movement of throttle valve 27 is effected by providing for orbital rotation of shaft 51 about the coincidental axes of shafts 48 and 54. Shaft 51 is supported by a cage having arms 55 and 56 loosely journaled on shafts 48 and 54, respectively, and having a yoke 57 supporting a gear segment 58 meshing with a gear 59 fixed to a shaft 60 connected by speed reducing gearing 61 with the shaft 62 of reversible electric motor 63.

50 Motor 63 comprises an armature 64, a shunt field 65 and a series field 66. Both fields are connected with a wire 67, connected by a switch 68 with a battery 70. Armature 64 is connected by brushes 71 and 72 with relay armatures 73 and 74, respectively, of relays 75 and 76, respectively, urged downwardly by springs 73a and 74a, respectively. Armatures 73 and 74 carry contacts 77 and 78, respectively, normally in engagement with contacts 79 and 80, respectively.

3

When relay magnet coils 81 or 82 are energized, armatures 73 and 74, respectively, move toward cores 83 and 84, respectively, to separate contacts 77 or 78, respectively, from contacts 79 or 80, respectively, and to move contacts 77 or 78 into engagement with contacts 85 or 86, respectively. Wires 87 and 88 connect contacts 85 and 86, respectively, with a wire 89 connected with a wire 90 leading from battery 70 to shunt field 66. Contacts 79 and 80 are connected by wires 91 and 92, respectively, with series field 66. Wire 89 is connected with relay coils 81 and 82. Relay coil 81 is connected by wire 93 with blade 94 of normally closed limit switch 95 connected by wire 96 with segment 38. Relay coil 82 is connected by wire 97 with limit switch 98 having a blade 99 connected by wire 100 with segment 39. Contact 101 resiliently biased toward the plate 37, is connected by wire 102 with wire 67.

Limit switches 95 and 98 are normally closed, but when the valve 27 is in idle position, for example, the insulated end of an arm 105 engages blade 99 to open switch 98 thereby preventing an operation of motor 63 which would tend to cause valve 27 to move further toward closed position. Likewise when valve 27 is wide open, arm 105 moves blade 94 down to open switch 95. Arm 105 is pivoted at 106 and is operated by a gear segment 107 meshing with a gear segment 108 connected with valve shaft 54.

When it is desired to ascend from ground level, lever 44 is moved clockwise to a position for selecting the manifold pressure required for "take-off." Cam 42 rotates clockwise to allow spring 41 to move lever 36 counterclockwise to bring contact segment 38 into engagement with contact 101. At the same time, this movement of lever 44 has caused valve 27 to be moved to an open position such that the manifold pressure becomes slightly less than the pressure selected for "take-off" and arm 105 moves away from blade 99 to permit switch 98 to close. The engagement of contacts 38 and 101 causes relay coil 81 to be connected with the battery 70. Armature 73 moves up to connect contacts 77 and 85 while armature 74 remains down to connect contacts 78, 80 then the direction of current flow through armature 64 is such as to cause gear 59 to rotate counterclockwise and gear segment 58 and shaft 54 and valve 27 to rotate clockwise to increase the manifold pressure. Bellow 32 expands to cause pivot 35 to move left and the contact 38 to move left away from contact 101. When contact 101 engages the gap or dead-spot 40, the motor 63 stops. Equilibrium is established when valve 27 has moved into such position that the manifold pressure is that selected by the setting of datum cam 42.

As the plane ascends, the tendency is toward a deficiency in manifold pressure. Hence bellow 32 tends to contract to move contact 38 into engagement with contact 101. Therefore, the motor 63 operates in the manner described to move the valve 27 wider open in order that the selected intake pressure will be maintained until the valve 27 is wide open. Then the limit switch 95 opens and the motor 63 is inoperative to effect a further clockwise movement of valve 27. The altitude at which the throttle 27 arrives at wide open position is the critical altitude for the pressure selected.

During descent, the tendency is toward an excess of intake pressure. The bellow 32 tends to

4

expand to move pilot 35 left to bring contact 39 into engagement with contact 101. The relay coil 82 is connected with the battery 70 to cause armature 74 to move up while armature 73 remains down. Contacts 77, 79 and 78, 86 are connected. Then the direction of current flow through the armature 64 is such as to cause the motor 63 to rotate gear 59 clockwise and the segment 58, the shafts 51 and 54 and the valve 27 counterclockwise to reduce the intake pressure to that which had been selected.

Therefore, between ground level and the critical altitude for a selected pressure, a selected intake pressure can be maintained. If a slight droop in selected pressure between ground level and critical altitude is desired, the external area of the aneroid bellows 31 can be made less than external area of the intake pressure responsive bellows 32.

In order that the engine output to the propeller may be controlled by the lever 44, the governed engine speed is caused to vary with the pressure selection according to a predetermined schedule. The coordination of pressure selection and governed speed adjustment is effected by a cam 161 driven by the shaft 43 which may be made as long as desired to accommodate the distance between the engine valve controller 30 and the propeller pitch changing lever 23.

The lever 23 is moved by a reversible electric motor 110 comprising an armature 111, a shunt field 112 and a series field 113. Wire 114 connects these fields with wire 67. Armature 111 is connected by brushes 121 and 122 with armatures 123 and 124, respectively, urged downwardly by springs 123a and 124a, respectively, and being parts of relays 125 and 126, respectively. Armatures 123 and 124 carry contacts 127 and 128, respectively, normally engaging contacts 129 and 130, respectively, but movable into engagement with contacts 135 and 136, respectively, in response to the energization, respectively, of coils 131 and 132, surrounding cores 133 and 134, respectively. Wires 137 and 138 connect contacts 135 and 136, respectively, with a wire 139 connected with wire 90 and battery 70. Wire 140 connects shunt field 112 with wire 139. Wire 141 connects contacts 129 and 130 with series field 113. Wires 145 and 146 connect relay coils 131 and 132, respectively, with limit-switch brushes 147 and 148, respectively, engaging segment contacts 149 and 150, respectively, carried by a non-conducting disc 151 driven by a shaft 152 connected by friction clutch discs 153 (urged into contact by a spring 153a) with a shaft 154 connected by speed reducing gearing 155 with motor shaft 156. Contacts 149 and 150 are engaged by brushes 157 and 158, respectively, connected by wires 159 and 160 respectively, with contact segments 161 and 162 insulatingly supported by a plate 163 with a gap or dead spot between them. Plate 163 is fixed to a shaft 164 fixed to an arm 165 carrying a roller 166 urged by spring 165a against the control cam 167 which is shaped so as to meet a predetermined schedule between pressure selections and governed engine speeds. Segments 161 and 162 are engaged selectively by a contact 170 carried by a disc 171 insulatingly supported by shaft 152 and driven thereby and engaged by a brush 172 connected with wire 114.

Shaft 152 is connected by arm 173, link 174, bellcrank 175 (pivoted at 176) and link 177 with 75 governed speed adjusting lever 23.

If cam 167 moves the plate 163 clockwise to bring contact 161 into engagement with contact 170, relay coil 131 is energized and relay armature 123 moves up while relay armature 124 remains down. Motor 110 causes shaft 152 to rotate clockwise until contact 170 moves to the dead-spot between the segments 161, 162. During this movement of shaft 152, the lever 23 moves counterclockwise to a position which will produce a governed speed corresponding to the pressure-speed schedule. If cam 167 moves the plate 163 counterclockwise to bring contact 162 into engagement with contact 171, relay coil 132 is energized and relay armature 124 moves up while relay armature 123 moves down. Then motor 110 causes shaft 152 to rotate counterclockwise until contact 170 moves to the dead-spot between the segments 161, 162. During this movement of the shaft 152, the lever 23 moves clockwise to a position which will produce a governed speed according to the pressure-speed schedule.

The main control lever 44 fixes the positions of the pressure-selecting cam 42 and the plate 163 according to the pressure-speed schedule. Motor 63 is under the control of cam 42 to maintain a selected pressure. Motor 110 is under the control of plate 163 to cause contact 170 to follow to the dead spot between contacts 161 and 162 in order to locate the speed adjusting lever in the required position to give the speed which matches the pressure selection.

This application is a continuation of application Serial No. 500,547, filed August 30, 1943, and now forfeited.

While the embodiment of the present invention as herein disclosed, constitutes a preferred form, it is to be understood that other forms might be adopted, all coming within the scope of the claims which follow.

What is claimed is as follows:

1. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, and means under control of the manually operable means and the pressure responsive means for controlling the operation of said electric motor.

2. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected and for effecting such other movements of the throttle as are necessary to

maintain the selected pressure during operation of the aircraft at different altitudes, means responsive to the engine intake pressure, and means under control of the manually operable means and the pressure responsive means for controlling the operation of said electric motor.

3. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, said movements of the valve by the manually operable means and the motor being independent of each other, means responsive to the engine intake pressure, and means under control of the manually operable means and the pressure responsive means for controlling the operation of said electric motor.

4. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected and for effecting such other movements of the throttle as are necessary to maintain the selected pressure during operation of the aircraft at different altitudes, said movements of the throttle valve by the manually operable means and the motor being independent of each other, means responsive to the engine intake pressure, and means under control of the manually operable means and the pressure responsive means for controlling the operation of said electric motor.

5. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected and means operable by the manually operable means for causing the motor to become operative to effect said additional movement of the throttle valve.

6. Apparatus for regulating the pressure in the intake conduit of a supercharged internal combustion engine having a throttle valve movable to different positions to variably control the engine intake pressure, a pressure selecting device

movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, means operable by the manually operable means for causing the motor to become operative to effect said additional movement of the throttle valve and means operable by the pressure responsive means to cause said motor to become inoperative when the throttle valve has been moved to the proper position to obtain the selected pressure.

7. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, circuits for controlling the operation of said motor, a control switch for controlling said circuits, means operable by the manually operable means to close said switch and cause the motor to become operative to effect said additional movement of the throttle valve, and means operable by the pressure responsive means to open said control switch and render the motor inoperative when said additional movement of the throttle has been completed.

8. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, and for effecting such other movements of the throttle as are necessary to maintain the selected pressure during operation of the aircraft at different altitudes, means responsive to engine intake pressure, circuits for controlling the operation of said motor, a control switch for controlling said circuits, means operable by the manually operable means to close said switch and cause the motor to become operative to effect said additional movement of the throttle valve, means operable by the pressure responsive means to open said control switch and render the motor inoperative when said additional movement of the throttle has been completed and the selected pressure obtained, said pressure responsive means being also operative to close the control switch upon operation of the aircraft at different altitudes in order to main-

tain the selected pressure during such operation.

9. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, circuits operable respectively for effecting operation of the motor in opposite directions to open and close the throttle valve, and means operable by the manually operable means when a pressure is selected to close the circuit causing operation of the motor in a direction to open the throttle and effect the additional opening movement thereof necessary to obtain the selected pressure.

10. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, circuits operable respectively for effecting operation of the motor in opposite directions to open and close the throttle valve, means operable by the manually operable means when a pressure is selected to close the circuit causing operation of the motor in a direction to open the throttle and effect the additional opening movement thereof necessary to obtain the selected pressure, means responsive to the engine intake pressure and means operable by said pressure responsive means for opening said last named circuit when the throttle has been opened sufficiently to obtain the selected pressure.

11. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, circuits operable respectively for effecting operation of said motor in opposite directions to open and close the throttle valve and means under control of the manually operable means and said pressure responsive means for controlling said circuits so as to determine the direction of operation of said motor and the extent of movement of the throttle valve by said motor.

12. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, circuits operable respectively for effecting operation of said motor in opposite directions for opening and closing the throttle valve, a two-way switch controlling said circuits comprising a member carrying spaced contacts and a contact member engageable with either of said spaced contacts and means under control of the manually operable means and the pressure responsive means for controlling the engagement of said contact member with one or the other of the fixed contacts to determine the direction of operation of the motor and extent of movement of the throttle valve.

13. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, circuits operable respectively for effecting operation of the motor in opposite directions to open and close the throttle, a two-way switch controlling said circuits comprising a member carrying spaced contacts and a contact member engageable with either one of said spaced contacts, a current source connected with said contact member, relays connected respectively with each of the spaced contacts and adapted to render one or the other of the motor circuits operative, and means under control of the manually operable means and the pressure responsive means for moving one of the switch members relative to the other in order to energize one or the other of said relays.

14. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, circuits operable respectively for effecting operation of the motor in op-

posite directions to open and close the throttle, a two-way switch controlling said circuits comprising a member carrying spaced contacts and a contact member engageable with either one of said spaced contacts, a current source connected with said contact member, relays connected respectively with each of the spaced contacts and adapted to render one or the other of the motor circuits operative, and means under control of the manually operable means and the pressure responsive means for moving the switch member carrying said spaced contacts relative to the other contact member so as to effect engagement of the latter with one or the other of said spaced contacts in order to energize one or the other of said relays.

15. Apparatus for regulating the pressure in the intake conduit of a supercharged internal combustion engine having a throttle valve movable to different positions to variably control the engine intake pressure, a pressure selecting device movable to select different intake pressures, manually operable means for actuating said device to select some desired pressure and effective to open the throttle valve sufficiently to obtain a pressure approaching that selected but always ineffective to move the valve enough to obtain the selected pressure, a reversible electric motor for effecting such additional movement of the throttle valve as is necessary to obtain whatever pressure is selected, means responsive to the engine intake pressure, circuits operable respectively for effecting operation of the motor in opposite directions to open and close the throttle, a two-way switch controlling said circuits comprising a member carrying spaced contacts and a contact member engageable with either of said spaced contacts, means operable by the manually operable means for effecting engagement of the contact member with one or the other of said spaced contacts when a pressure is selected, means operable by the pressure responsive means for disengaging said contacts when the motor has moved the throttle valve sufficiently to obtain the pressure selected, said last named means being also operable by the pressure responsive means to effect engagement of the contact member with one or the other of said spaced contacts when the intake pressure varies from that selected.

16. An engine throttle valve controller for use with a supercharged airplane engine comprising the combination with the throttle valve, of a main control lever, a reversible electric motor, a mechanism including aligned shafts connected, respectively, with the lever and valve and gearing connecting the shafts including a counter-shaft and connected gears thereon and gears attached, respectively, to the aligned shafts and meshing, respectively, with the gears on the counter-shaft whereby motion is transmitted from the lever to the valve, said mechanism including a frame supporting the counter-shaft for rotation about the aligned shafts and means operated by the motor for rotating the frame whereby motion is transmitted to the valve from the motor, an element responsive to engine intake pressure and means for controlling the operation of the motor, said means being under the control of the lever and the intake-pressure-responsive element.

17. An engine throttle valve controller for use with a supercharged airplane engine comprising the combination with the throttle valve, of a main control lever, a reversible electric motor, means for transmitting motion from the lever to the

valve independently of the motor, means for transmitting motion from the motor to the valve independently of the lever, an element responsive to engine intake pressure, circuits operable respectively for effecting operation of the motor in opposite directions, a two-way switch comprising a member and spaced contacts insulatingly supported thereon and a contact member engageable with either of the contacts of the first member or with neither, a current source connected with the second member, relays connected respectively with the contacts on the first member, and operable respectively to render operative the motor control circuits, a datum or pressure-selecting cam operated by the main control lever, and a second lever positioned by the datum cam and by the intake-pressure-responsive element for moving one of the two-way switch members relative to the other switch member.

18. An engine throttle valve controller for use with a supercharged airplane engine comprising the combination with the throttle valve, of a main control lever, a reversible electric motor, means for transmitting motion from the lever to the valve independently of the motor, means for transmitting motion from the motor to the valve independently of the lever, an element responsive to engine intake pressure, circuits operable respectively for effecting operation of the motor in opposite directions, a two-way switch comprising a member and spaced contacts insulatingly supported thereon and a contact member engageable with either of the contacts of the first member or with neither, a current source connected with the second member, relays connected respectively with the contacts on the first member and operable respectively to render operative the motor control circuits, a datum or pressure-selecting cam operated by the main control lever, and a second lever having a floating fulcrum positioned by the intake-pressure-responsive element and having an arm engaging the datum cam, said second lever effecting the movement of one of the two-way switch members relative to the other switch member.

19. An engine throttle valve controller for use with a supercharged airplane engine comprising the combination with the throttle valve, of a main control lever, a reversible electric motor, means for transmitting motion from the lever to the valve, independently of the motor, means for transmitting motion from the motor to the valve independently of the lever, an element responsive to engine intake pressure, circuits operable

respectively for effecting operation of the motor in opposite directions, a two-way switch comprising a member and spaced contacts insulatingly supported thereon and a contact member engageable with either of the contacts of the first member or with neither, a current source connected with the second member, relays connected respectively with the contacts on the first member and operable respectively to render operative the motor control circuits, a datum or pressure-selecting cam operated by the main control lever, and a second lever having a floating fulcrum positioned by the intake-pressure-responsive element and having an arm engaging the datum cam, said second lever providing the first mentioned member of the two-way switch.

20. An engine throttle valve controller for use with a supercharged airplane engine comprising the combination with the throttle valve, of a main control lever, a reversible electric motor, means for transmitting motion from the lever to the valve independently of the motor, means for transmitting motion from the motor to the valve independently of the lever, aligned bellows having remote ends fixed and adjacent ends connected by a bridge, one of the bellows being evacuated and the other being connected with the engine intake, circuits operable respectively for effecting operation of the motor in opposite directions, a datum or pressure-selecting cam operated by the main control lever, a second lever positioned by the cam and pivotally supported by the bellows bridge whereby the second lever is controlled by the main control lever and by engine intake-pressure, a two-way switch comprising spaced contacts insulatingly supported by the second lever and a third contact engageable with either of the contacts supported by the second lever or with neither, a current source connected with the third contact, and relays connected respectively with the contacts supported by the second lever and operable respectively to render operative the motor control circuits.
